MULTIPLE-LOBE ANTENNA ASSEMBLY

Philip J. Allen, Washington, D. C.

Application October 6, 1949, Serial No. 119,982

7 Claims. (Cl. 250—33.63)

(Granted under Title 35, U. S. Code (1952),
sec. 266)

1

This invention relates to antenna systems and more particularly to multiple-lobe antenna assemblies.

Prior systems for obtaining indications of the position of a reflecting surface or energy source in space through the use of electromagnetic energy waves usually employ a group of four directional transmitting or receiving antennas operable to derive signals indicative of the reflecting surface or energy source position with respect to equally spaced axes of directivity of the antennas. The accuracy of the indications is partially determined by the separation between the axes of directivity, and therefore the antennas are mounted in the closest physical relationship permitted by their structural characteristics.

The prior systems of the foregoing character which operate in response to transmitted signals employ a fifth directional antenna, usually similar to the antennas of the group, functioning as a transmitting or a receiving element, necessarily symmetrically positioned with respect to the antennas of the group. The resulting structure is not only bulky and produces effects which tend to decrease tracking efficiency, but also increases separation between the equally spaced axes of directivity by an amount at least equal to the dimensions of the fifth antenna element.

It is therefore an object of the present invention to provide a novel multiple-lobe antenna assembly free from the foregoing disadvantages.

Another object is to provide a novel multiple-lobe antenna assembly having a plurality of equally spaced axes of directivity with minimum separation therebetween, and an axis of directivity symmetrically positioned thereof.

Another object is to provide a novel antenna assembly providing a plurality of symmetrical directional lobe patterns with minimum separation between the directivity axes thereof, and a single directional lobe pattern having an axis of directivity equally spaced from the axes of directivity.

Still another object of the present invention is to provide a multiple-lobe antenna assembly comprising a plurality of symmetrically juxtaposed electromagnetic horns establishing a plurality of symmetrical lobe patterns having minimum separation between the axes of directivity thereof, and a single antenna element positioned centrally of the horns having a directional lobe pattern positioned symmetrically with respect to said patterns.

Still another object is to provide an antenna assembly of the foregoing character wherein the

single antenna element does not substantially effect the separation between the directivity axes of the patterns.

Still another object is to provide four sectoral electromagnetic horns symmetrically secured together in juxtaposition and a single antenna element positioned centrally of the horns within the flare portions thereof.

Other objects and features of the present invention will appear more fully hereinafter upon consideration of the following detailed description in connection with the accompanying drawings which disclose one embodiment of the invention. It is expressly understood however that the drawing is designed for purposes of illustration only and not as a definition of the limits of the invention, reference for the latter purpose being had to the appended claims.

In the drawings, wherein similar reference characters denote similar elements throughout the several views:

Fig. 1 is a perspective view of a multiple-lobe antenna assembly constructed in accordance with the principles of the present invention;

Fig. 2 is a front view of the antenna assembly of Fig. 1, and

Fig. 3 is a perspective view, partly in section, of a portion of the antenna assembly illustrated in Fig. 1.

With reference more particularly to Figs. 1 and 2 of the drawings, an antenna assembly constructed in accordance with the principles of the present invention is disclosed therein including four electromagnetic sectoral horns 10, 11, 12 and 13, constructed of metallic material. The horns are symmetrically joined together in juxtaposition at the mouth sections 14 thereof to form a unitary structure having a frontal area equal to the combined mouth areas of the sectoral horns.

Each of the sectoral horns includes a pair of flare portions 15, a pair of unflared side portions 16 and a throat section 17. The flare portions 16 increase the aperture of the horns in the direction of the electric vector in the case of electric plane horns, and when magnetic plane horns are employed the horn apertures are increased in a direction perpendicular to the electric vector. Electromagnetic energy is fed to the horns 10, 11, 12 and 13 through rectangular wave guides 18, 19, 20 and 21, operating at the proper mode for the type of horns employed, coupled to the respective throat sections 17 in a conventional manner.

The foregoing construction comprises an antenna assembly having four symmetrically

spaced directional lobe patterns with absolute minimum separation between the directivity axes thereof.

As mentioned heretofore, it is an object of the present invention to provide an antenna assembly having a plurality of symmetrical directional lobe patterns with minimum separation between the directivity axes thereof, with novel means for producing a single directional lobe pattern symmetrically positioned with respect to the plurality of patterns without substantially effecting the separation between the directivity axes thereof.

The foregoing means comprises a rod-type dielectric directional antenna element 22, constructed of polystyrene, or any other suitable dielectric material, positioned centrally of the sectoral horns with its longitudinal axis, or its axis of directivity, lying symmetrical with respect to the directivity axes of the horns. The juxtapositioned flare portions 15 and unflared side portions 16 are uniformly cut away about the center of the unitary structure throughout the length thereof to provide space for a metallic tubular member 23 supporting the dielectric antenna element 22. The metallic tubular member 23 is secured to the cut edges of the flare portions 15 and the unflared side portions 16, and extends from a plane spaced from the mouth sections 14, through the unitary structure in symmetrical relation with the axes of directivity, and terminates in coupling relation with a rectangular wave guide 24.

Fig. 3 of the drawing discloses the structural relationship between the metallic tubular member 23 and the wave guide 24, and the energy coupling means between the dielectric antenna element 22 and the wave guide 24. As shown, the end of the wave guide 24 adjacent the plane of the throat sections 17 is closed by a metallic plate 25 having a centrally located circular opening therein coextensive with the internal diameter of the tubular member 23, and the dielectric antenna element 22 extends throughout the length of the tubular member 23 and terminates in the plane of the wall 25 with a cylindrical portion 26, of reduced diameter, projecting into the wave guide 24. The length and diameter of the portion 26 is selected to provide proper impedance matching at the operating frequency. It is expressly understood that adequate coupling may be provided between the dielectric antenna element 22 and the wave guide 24 by terminating the radiating element 22 within the wave guide 24 perpendicular to the wall 25, or by other means well known to the art.

As shown particularly in Fig. 2, the metallic tubular member 23 is positioned centrally of the sectoral horns within the flare portions 15 and without the throat sections 17. This feature of the invention, in addition to the fact that the tubular member 23, with the dielectric antenna element 22, occupies a relatively small portion of the total projected area of the flare portions 15, provides a multiple-lobe antenna assembly wherein the centrally positioned antenna element 22 has substantially no effect upon directivity characteristics or attenuation. Moreover, any change in directivity or attenuation effects all horns equally, and therefore the optimum comparative directivity characteristic obtained by joining the horns in symmetrical juxtaposition is not effected thereby.

It is expressly understood that the antenna assembly may be constructed in any convenient manner, for example, by building up four sectoral

horns from the centrally located tubular member instead of joining four horns as described heretofore, that a plurality of electric plane horns, magnetic plane horns, compound horns or conical horns derived from circular wave guides, may be formed or juxtaposed in symmetrical relation, and that the centrally positioned antenna element may comprise other shapes of dielectric material, such as rectangular for example, as well as other types of end-fired elements. Moreover, the sectoral horns may be employed to receive electromagnetic energy with the rod 22 functioning as a radiating element, or vice versa, and the assembly may be employed as a feed to illuminate a reflector or lens, or as a terminal antenna element.

There is thus provided by the present invention a novel multiple-lobe antenna assembly for providing a plurality of symmetrical directional lobe patterns having minimum separation between the axes of directivity thereof, and a single directional lobe pattern positioned symmetrically of the patterns without effecting the separation between the axes of directivity or the characteristics of the lobe patterns, and without substantially increasing energy attenuation. Multiple-lobe antenna assemblies constructed in accordance with the principles of the present invention are inherently less bulky than systems provided heretofore and are more readily adapted for use with precision tracking mechanisms.

Although only one embodiment of the present invention has been disclosed and described herein it is expressly understood that various changes and substitutions may be made therein without departing from the spirit of the invention as well understood by those skilled in the art. Reference therefore will be had to the appended claims for a definition of the limits of the invention.

The invention described herein may be manufactured and used by or for the Government of the United States of America for governmental purposes without the payment of any royalties thereon or therefor.

What is claimed is:

1. A multiple-lobe antenna assembly comprising a plurality of antenna elements each providing a directional lobe pattern, separate wave guides connected to each of said antenna elements, means mounting said antenna elements relative to each other to establish minimum separation between the axes of directivity of each of said patterns, a single antenna element providing a single directional lobe pattern, and mounting means supporting said single antenna element on said plurality of antenna elements with the single directional lobe pattern thereof symmetrically positioned with respect to the directional lobe patterns of said plurality of antenna elements and still another wave guide connected to said single antenna element.

2. An antenna assembly comprising a plurality of electromagnetic horns joined together to form a unitary structure having a frontal area substantially equal to the combined mouth areas of said horns, and an end-fired antenna element mounted centrally of said structure.

3. An antenna structure comprising a plurality of electromagnetic horns each having a flare portion and a mouth section, means symmetrically mounting said horns in contact at said mouth sections to form a unitary structure having a plurality of axes of directivity equally-distant from the center thereof, each of said horns hav-

ing a corresponding portion thereof adjacent the center of said structure removed to define an opening lying longitudinally of said horns within the flare portions thereof, separate wave guides connected to each of said horns, an antenna element positioned in said opening, and still another wave guide connected to said antenna element.

4. An antenna assembly comprising a metallic tube terminating a wave guide and supporting a dielectric antenna element, and four electromagnetic horns mounted in quadrature about said tube with each quadrant of said tube comprising a portion of the flare of one of said horns, and separate wave guides connected to each of said horns.

5. An antenna assembly comprising four electromagnetic horns joined together in quadrature relationship at the mouth sections thereof with symmetrical axes of directivity, separate wave guides connected to each of said horns, a tubular member positioned centrally of said horns and extending into said horns symmetrically of said axes within the flare portions thereof, and a dielectric antenna element carried by said tubular member, and still another wave guide connected to said antenna element.

6. A microwave antenna assembly comprising a plurality of similar electromagnetic horns each having flare portions and mouth sections, separate wave guides connected to each of said horns, means joining said horns in juxtaposition at said mouth sections, and a rod-type dielectric antenna

element having a diameter less than twice the small dimension of the projection of any one of said flare portions to the plane of said mouth sections positioned centrally of said horns, and still another wave guide connected to said antenna element.

7. A microwave antenna assembly comprising a plurality of electromagnetic horns each having flare portions and mouth and throat sections, separate wave guides connected to each of said horns, means joining said horns in juxtaposition at said mouth sections, and an end-fired antenna element positioned centrally of said horns and extending longitudinally through said horns within the flare portions and without the throat sections thereof, and still another wave guide connected to said antenna element.
